HAMMER FOR IMPACT CRUSHERS WITH
DETACHABLE AND REVERSIBLE HAMMER
HEADLeslie G. Ehmann, Portland, Oreg., assignor to
Electric Steel Foundry, Portland, Oreg., a cor-
poration of Oregon

Application December 10, 1943, Serial No. 513,759

10 Claims. (Cl. 241—194)

1

This invention relates to rotary impact crushers of the type commonly used to crush or pulverize rock, coal, cement and similar substances, and more specifically to a new and improved hammer for use therein.

Rotary impact crushers usually comprise a rotor element mounted within a generally cylindrical cage formed of breaker bars, said rotor element comprising a plurality of discs mounted in spaced relation on a driven shaft and having a plurality of hammers pivotally attached to the rotor element adjacent the periphery of the discs. The rotor element is driven at high speed and material fed thereto is crushed or pulverized between the hammers and the cage. Each row of hammers usually is attached to the rotor element by means of a single pivot shaft extending through openings near the periphery of the discs, with the hammers mounted on the shaft between the discs.

Impact hammers embodying the present invention are adapted for use in various types and kinds of crushers and reducers, the leading edges of the hammers being subject to considerable wear under impact with the material being crushed. It becomes desirable, therefore, to periodically reverse the position of the head on the shank to provide for more even wear of the hammer head, and to replace the head portion entirely when worn to such an extent as to make further use impractical. With the various types of hammers in use heretofore it has been necessary to remove the pivot shaft from the rotor element in order to reverse or replace the head portion of the hammer. This operation requires the dismantling of a considerable portion of the machinery comprising the rotor element, and is the cause of considerable delays in the operation of the crusher, and usually requires the use of special tools.

In view of the above, an object of the present invention is to provide a hammer adapted for use in rotary impact crushers, of which the head portion may be reversed or replaced in a minimum length of time without the use of special tools and without detaching the shank portion of the hammer from the shaft which connects it to the rotor assembly.

A further object of the invention is to provide a reversible type hammer head which may be so attached to the shank portion that none of the stresses imposed upon the head are imparted to the fastening means.

It is a further object of the invention to provide a reversible type hammer head which may be detachably secured to the shank portion in such manner as to preclude the head becoming de-

2

tached from the shank during operation of the crusher.

A further object of the invention is to provide a reversible type hammer head so constructed as to provide for a maximum amount of surface wear before necessitating replacement.

These and other features of the invention are fully described in the following paragraphs, reference being made to the accompanying drawings

10 in which:

Figure 1 is an end view of the rotor element of a rotary crusher showing the relative positions of four rows of hammers of a type embodying the present invention; Figure 2 is a longitudinal view, 15 approximately on the line 2—2 of Figure 1, of a portion of a crusher illustrating the arrangement of a row of hammers therein; Figure 3 is a perspective view, partly in section, of a hammer head; Figure 4 is a perspective view of a hammer shank showing the locking pin being assembled; Figure 5 is a fragmentary sectional view of a hammer shank showing the manner in which the hole for admitting the locking pin is closed permanently after assembly to prevent displacement 20 of the pin; Figure 6 is a perspective view, partly in section, of a hammer embodying the present invention, illustrating the same as being mounted in working position on the pivot shaft of a rotary crusher; Figure 7 is a perspective view, partly in 25 section, similar to Figure 6, showing the manner of unlocking the hammer head from the shank for reversing or replacing the same without disassembling the shank from the pivot shaft; and Figures 8 and 9 illustrate a sectional elevation of 30 a hammer showing a modified construction embodying the invention and the manner of unlocking the hammer head.

In Figures 1 and 2 is shown portions of a rotor element such as used in a crusher of conventional design. The rotor comprises a driven shaft 10 having a plurality of discs 11 mounted thereon and keyed thereto, each of the several discs having axially extending hub portions 12 by reason 40 of which the discs are positioned on the shaft in spaced apart relation. Each disc is provided adjacent its periphery with openings 13 spaced ninety degrees apart for reception therethrough of pivot shafts 14 on which are mounted the shanks 15 of a plurality of hammers embodying the instant invention. The hammers are mounted between each adjacent two of the discs 11, the shanks extending between the discs for engagement with the pivot shafts 14. Each of the 45 shanks 15 is provided with an eye 16 for receiving

therethrough the pivot shaft 14 by which the hammer is secured to the rotor element.

Each of the hammers comprises a shank portion 15 for attachment to the rotor element in the manner above described, and a head portion 21 detachably fastened to the shank portion by a locking device presently to be described. The shank portion 15 is of one piece construction and comprises an elongated body of generally rectangular shape having at one end thereof an eye 16 for the reception of the pivot shaft 14 and provided at the opposite end thereof with an elongated slot 17 extending transversely through the outer end 18 of the shank, the axis of the slot 17 being parallel with the axis of the eye 16. The shank 15 is formed with an enlargement intermediate its ends providing shoulders 19 encircling opposite edges of the shank and facing in the direction of the slotted outer end 18 for insuring a proper seating relation between the head 21 and the shank 15. The outer end 18 of the shank forms a projection extending outwardly from the shoulders 19 and is adapted to be received in a recess 26 in the hammer head 21.

A bore 22 is provided longitudinally of the shank 15, and mounted within the bore 22 and having free movement longitudinally thereof is a locking pin 23. At the outer end of the shank the bore 22 opens into the slot 17, while at the inner end of the shank the bore 22 opens into the eye 16. The locking pin 23 is made somewhat longer than the length of the bore 22 and projects either into the slot 17 or into the eye 16, as the case may be. The locking pin 23 is not of sufficient length, however, to project into both the slot 17 and the eye 16, so that when the end of the pin projects into the slot 17, for example, the opposite end of the pin is received into the body of the shank.

The hammer head 21 comprises a work performing portion 24 positioned away from the shank, and a shank end receiving portion 25 positioned toward the shank and having a central open recess 26 within said shank end receiving portion of such size as to receive therein the slotted end 18 of the shank, whereby the several parts may be assembled into one operating unit. In the construction illustrated in the drawings, the recess 26 is defined by end walls 27 and side walls 28. The walls 27 and 28 terminate in shoulders 29 which lie in the plane of the inner surface of the hammer head and cooperate with the shoulders 19 on the shank 15 to prevent a rocking motion between the shank 15 and the head 21 when in operation. The side walls 28 of the recess 26 in the hammer head are provided with aligned slots 31 which, when the shank 15 and head 21 are assembled, are in alignment with the slot 17 in the end portion 18 of the shank, thus providing a continuous opening extending entirely through the hammer head 21. An advantage of this construction lies in the fact that the recess 26 in the hammer head may be relatively shallow, as compared to the work performing portion 24 of the head, and so provides a maximum amount of wearing surface, which reduces operating costs by reason of the longer use of the head before replacement is necessary.

For locking the hammer head 21 on the end of the shank 15 there is provided a key 32 of such shape as to conform to the opening through the hammer head formed by the aligned slots 31 and 17 when the hammer head and shank are in assembled relation. The key 32 is provided with a through hole 33 which, when the key is

in proper position, is in alignment with the longitudinal bore 22 in the shank 15 in which is mounted the locking pin 23. When the key 32 is inserted in the aligned slots 31 and 17 the locking pin 23 drops into the through hole 33 in the key and prevents displacement of the key from the aligned slots. In that embodiment of the invention illustrated in Figures 6 and 7 the locking pin 23 is of such length that when the outer end thereof is in engagement with the key 32 the inner end of the pin is flush with the peripheral wall surface of the eye 16 so that the presence of the pivot shaft 14, by which the hammers are secured to the rotor element of the crushing device, prevents longitudinal movement of the locking pin in the bore 22, thus insuring against displacement of the key 32. The key, in turn, securely locks the hammer head 21 to the shank 15 and prevents any of the parts becoming displaced during operation of the crusher.

The shank 15 is provided with a transverse bore 34 communicating with the longitudinal bore 22 which provides access to the locking pin 23 in the event accumulations of material in the bore 25 may require manual effort to move the pin.

In Figures 4 and 5 is illustrated the manner of assembling the locking pin 23 in the longitudinal bore 22. When the shank 15 is cast the bore 22 is made to extend through the end 18 of the shank, i. e., through the portion forming the outer wall of the transverse slot 17. Thereupon the locking pin 23 is placed in the longitudinal bore 22 and the opening in the end of the shank is permanently closed as by welding a plug 30 therewithin. The locking pin is of lesser diameter than the diameter of the bore 22 and has free movement longitudinally therein, the pin being retained in the bore by the plug 30 at the outer end of the shank and by that portion of the inner end of the shank forming the wall of the eye 16.

Figures 6 and 7 illustrate a construction in which the pivot shaft 14, extending longitudinally of the rotor element through aligned openings 13 in spaced discs 11, is provided with notches 35 which are spaced longitudinally of the shaft a distance corresponding to the distance between the locking pins 23 in adjacent hammers. Each notch 35 is of sufficient size to receive therewithin the end of a locking pin 23, and is of such depth that when the inner end of the locking pin 23 drops into the notch 35 the opposite end of the locking pin disengages the key 32, permitting the key to be removed from the hammer head to permit removal of the head from the shank.

In assembling the hammers in the crusher, each row of hammers is mounted on the rotor element by inserting the pivot shaft 14 alternately through openings 13 in the discs 11 and through the eyes 16 in the shanks 15. With the rotor element rotated to the position illustrated in Figures 6 and 7, wherein the hammers may extend vertically from the rotor element with the hammer head 21 uppermost, the pivot shaft 14 is moved longitudinally of the rotor element to bring the several notches 35 into registry with the longitudinal bores 22 in the shanks 15. In this position the inner end of each locking pin 23 drops into one of the notches 35, thus clearing the slot 17 in the outer end of the shank for insertion of the key 32. Thereupon the hammer head 21 is placed on the shank, the end of the shank being received in the recess 26 with the slot 17 in the end of the shank aligned with the slots 21 in the side walls 28 of the head. Thereupon the key 32 is inserted in the aligned slots 31 and 17 and

the locking pin 23 is moved longitudinally of the bore 22 and caused to engage through the hole 33 in the key 32. This movement of the locking pin causes the inner end of the pin to disengage the notch 35 in the pivot shaft, whereupon the pivot shaft 14 may be moved into the position shown in Figure 6, in which position the inner end of the locking pin 23 rides upon the outer surface of the shaft 14 and is prevented from disengaging the key 32. The shaft 14 may be secured in the final assembled position by means of a screw 36 extending diametrically from the periphery of the outer disc 11 into the registering notch 35 in the pivot shaft 14.

At such times as the hammer heads are to be reversed or replaced, or at the time of the initial assembly of the machine, the rotor element might well be rotated to the position shown in Figures 6 and 7 to permit the hammers to extend vertically from the upper side thereof with the heads 21 in the uppermost position. Thereupon the screw 36 is withdrawn from engagement with the outermost notch 35 and the pivot shaft 14 is moved longitudinally of the rotor element to place the notches 35 in registry with the longitudinal bores 22 in the several shanks 15. When this occurs the locking pins 23 drop into the notches 35 and disengage the keys 32 which may then be removed from the aligned slots 34 and 17 to release the hammer heads. The hammer heads may then be either reversed or replaced as required. When the hammers have been reassembled and the key 32 shall have been reinserted in the aligned slots 34 and 17, the rotor element may be rotated through an angle of 180 degrees to cause the several locking pins 23 to drop into the hole 33 in the key and disengage the several notches 35 in the pivot shaft 14. Thereupon the pivot shaft is moved longitudinally of the rotor element to disalign the notches 35 and the longitudinal bores 22 in the shanks 15 and to bring the outermost notch 35 into registry with the screw 36 which is then turned down to engage the notch to prevent longitudinal movement of the shaft during operation of the device.

Referring now to Figures 8 and 9, there is shown a portion of a rotor element for a rotary crusher comprising spaced discs 37 and a longitudinally extending pivot shaft 38 as in the construction hereinabove described. Mounted on the pivot shaft 38 is shown a hammer embodying the present invention. The hammer comprises a shank 39 having an eye 41 provided in its inner end for the reception of the pivot shaft 38, and an outer end portion 42 extending outwardly from shoulders 43. The outer end 42 of the shank is provided with a transverse slot 44 disposed intermediate the plane of the shoulders 43 and the extreme end surface of the shank. The shank is provided with a longitudinal bore 45 communicating at its outer end with the transverse slot 44. Mounted in the longitudinal bore for free movement longitudinally thereof is a locking pin 46 adapted for engagement with the key 47 by means of which the hammer head 48 is secured to the shank.

The shank is provided intermediate its ends with a transverse bore 49 communicating with the longitudinal bore 45. One end of the transverse bore 49 is threaded for the reception of a screw plug 51.

The hammer head 48 comprises a work performing portion 52 positioned away from the shank, and a shank end receiving portion 53 positioned toward the shank, the shank end re-

ceiving portion defining a recess 54 for receiving therein in closely fitting engagement therewith the outer end 42 of the shank 39. The recess is defined by walls 55 through which extend transverse slots 56 which register with the slot 44 in the end of the shank 39 when the hammer head is in working position.

With the outer end 42 of the shank 39 fitted into the recess 54 of the hammer head 48, in which position the slots 44 and 56 are in alignment, the key 47 is inserted in the aligned slots to secure the head to the shank. The key 47 is provided with a center hole 57 adapted to receive the end of the locking pin 46 to prevent displacement of the key.

The locking pin 46 is of such length as to bear at one end against the outer wall 58 of the transverse slot 44 in the end of the shank, and to bear at the other end against a shoulder 59 on the screw plug 51. With the key 47 inserted in the aligned slots 44 and 56, the locking pin 46 enters the hole 57 in the key 47 and is held therein by the shoulder 59 on the plug 51. To release the key 47 the screw plug 51 is backed up sufficiently to withdraw the shoulder 59 from the longitudinal bore 45, whereupon the locking pin 46 may drop out of engagement with the key 47 to permit removal of the key from the aligned slots 44 and 56, thus releasing the head 48. The locking pin 46 is chamfered at its outer end to provide a shoulder 61 by which the pin may be engaged to withdraw it from engagement with the key in the event an accumulation of dust or other matter may tend to plug the longitudinal bore 45.

In the manufacture of the hammers shown in Figures 8 and 9, the shank 39 is cast with the longitudinal bore 45 extending from the eye 41 in the inner end of the shank to the transverse slot 44 in the outer end of the shank, the longitudinal bore communicating with both the eye 41 and the slot 44. It will be noted that the length of the locking pin 46 is slightly less than the diameter of the eye 41, and in assembling the shank the locking pin is inserted in the longitudinal bore 45 through the end thereof which communicates with the eye 41. Thereupon the longitudinal bore 45 is plugged at the point of its intersection with the transverse bore 49, as by means of a plug 62, for preventing loss of the locking pin from the longitudinal bore by way of the eye 41. The locking pin is of lesser diameter than the longitudinal bore 45 and is permitted free longitudinal movement therein, being retained therein by means of the plug 62 intermediate the length of the bore, and by the end portion of the shank forming the outer wall of the transverse slot 44.

To reverse or replace a head 48 on a shank 39 the plug 51 is unscrewed from the threads in the end of the transverse bore 49 a sufficient distance to clear the pin 46, whereupon an appropriate tool, or even a finger, may be inserted into the opposite end of the transverse bore 49 to engage under the shoulder 61 on the pin 46 to withdraw the pin from the hole 57 in the key 47. If convenient, the rotor element may be rotated to the position illustrated in Figures 8 and 9 to permit the hammers to extend vertically from the upper side thereof with the heads 48 in the uppermost position. In such position, when the plug 51 is backed out of the transverse bore 49 the locking pin 46 will drop out of engagement with the key 47 and the key be thereupon removable to release the head as shown in Figure 9. When the head shall have been re-

versed or replaced and the key reinserted in position to engage the aligned slots 44 and 58, the locking pin may be moved to extend through the hole 57 in the key and the plug 51 threaded into the transverse bore 49 to retain the pin in locking engagement with the key.

An important advantage of the invention is that it precludes the necessity of disconnecting the shank portion of the hammer from the rotor element when reversing or replacing the head, which permits such repairs to be made within a minimum period of time and without the use of special tools. A further advantage is that no strain is placed on the locking pin during operation of the crusher, the resulting stresses being absorbed by the key member which locks the head on the shank.

There is herein shown and described a particular embodiment of the invention, illustrating the principle thereof as applied to a hammer for impact crushers. It will be understood, however, that the invention is applicable to other structures embodying a releasable fastening means for a detachable part, and that various changes in form, proportion, size and details of construction within the scope of the claims may be resorted to without departing from the spirit or sacrificing any of the advantages of the invention.

Having now described my invention and in what manner the same may be used, what I claim as new and desire to protect by Letters Patent is:

1. A hammer for impact crushers comprising a shank, a hammer head replaceably mounted on the end of said shank, said shank comprising an inner end having an eye therethrough for mounting said shank on the pivot shaft of a rotor element in a rotary crusher and an outer end having a slot extending therethrough, a bore extending longitudinally of said shank and opening into said slot, a locking pin disposed in said bore and having free movement longitudinally thereof, the head comprising a work performing portion positioned away from the shank, a shank end receiving portion positioned toward the shank, a central open recess within said latter portion of such size as to receive therein the outer end of said shank, said recess having opposite wall portions, aligned slots extending through said wall portions, the slot in the outer end of said shank being in alignment with the slots in said walls when said shank and head are in assembled relation, a key insertable into the opening formed by said slots for locking said head on said shank, a through hole in said key for receiving the end of said locking pin when said key is in said opening, and means movable into engagement with the opposite end of said pin for releasably holding said pin in engagement with said key.

2. A centrifugal hammer comprising a shank, means adjacent one end of said shank for mounting said shank on the rotor element of a rotary crusher, means defining a slot extending through said shank adjacent the opposite end thereof, a bore extending longitudinally of said shank and opening into said slot, a locking pin disposed in said bore and being movable longitudinally thereof, a hammer head replaceably mounted on the slotted end of said shank comprising a work performing portion positioned away from the shank, a shank end receiving portion positioned toward the shank, a central open recess within said latter portion for receiving therein in closely fitting engagement therewith the slotted end of said shank, said recess having opposite wall por-

tions, aligned slots extending through said wall portions, the slot in the end of said shank being in alignment with the slots in said walls when the shank and head are in assembled relation, a key insertable into the opening formed by said slots for locking said head on said shank, said locking pin being movable into locking engagement with said key when said key is in said opening, and means for releasably holding said pin in engagement with said key.

3. A centrifugal hammer comprising a shank and a hammer head replaceably mounted on said shank, upstanding walls on said head defining a recess therebetween, means defining aligned openings extending through said walls, said shank comprising an end portion adapted to be received in said recess between said walls, means defining an opening through the head engaging portion of said shank, a bore disposed longitudinally of said shank extending into said opening, the opening in said shank being in alignment with the opening in said walls when said shank and head are in assembled relation, a key insertable into the opening through said assembled shank and head for locking said head on said shank, and a pin slidably mounted in said bore and movable into the opening in said shank for engaging said key, and means for releasably holding said pin in engagement with said key.

4. A centrifugal hammer comprising a shank member and a head member replaceably mounted thereon, a coupling for detachably locking said members in operative relation, said coupling comprising upstanding walls on one of said members defining a recess therebetween, aligned openings extending through said walls, a portion of the other of said members adapted to be received in said recess between said walls and having an opening extending therethrough, the openings in both said members being in alignment when said members are in assembled relation, a key insertable into said openings, and means carried by said shank member and movable into engagement with said key for releasably holding said key in said openings, said means being shrouded by said shank member and slideable therewithin for movement between positions of engagement and disengagement with said key.

5. A coupling means for detachably coupling separable parts in united operative relation, comprising a part having upstanding walls defining a recess, aligned openings extending through said walls, a second part having an end portion adapted to be received in said recess and having an opening extending therethrough, a bore in said second part extending into said opening, the opening in said second part being in alignment with the openings in said walls when said parts are in assembled operative relation, a key insertable into the opening through said assembled parts for locking said parts in operative relation, and a pin slidably mounted in said bore and movable into engagement with said key for releasably holding said key in said locking position.

6. In a rotary crusher, a rotor element having a shaft, a plurality of hammers mounted on said shaft, each said hammer comprising a shank and a head replaceably mounted on said shank, said shank and said head having interengaging parts for mounting said head on said shank, means defining openings through each of said interengaging parts, said openings being in alignment when said shank and head are mounted in operative relation, a key insertable in said open-

ings for detachably locking said head on said shank, means mounted in said shank for holding said key in said aligned openings, and means mounted in said shank for releasably holding said last named means in engagement with said key.

7. In a rotary crusher, a rotor element having a shaft, a plurality of hammers mounted on said shaft, each said hammer comprising a shank and a head replaceably mounted on said shank, said shank and said head having interengaging parts for mounting said head on said shank, means defining openings through each of said interengaging parts, said openings being in alignment when said shank and head are mounted in operative relation, a key insertable in said openings for detachably locking said head on said shank, a pin mounted in said shank for holding said key in said aligned openings, and means mounted in said shank for releasably holding said pin in engagement with said key.

8. In a rotary crusher, a rotor element having a shaft, a plurality of hammers mounted on said shaft, each said hammer comprising a shank and a head replaceably mounted on said shank, said shank and said head having interengaging parts for mounting said head on said shank, means defining openings through each of said interengaging parts, said openings being in alignment when said shank and head are mounted in operative relation, a key insertable in said openings for locking said head on said shank, a pin mounted in said shank for holding said key in said aligned openings, and means defining a recess in said shaft into which said pin may be moved to release said key, said shaft being movable relative to said rotor element to move the recess in said shaft into alignment with said pin.

9. In a rotary crusher, a rotor element having a shaft, a plurality of hammers mounted on said shaft, each said hammer comprising a shank and a head replaceably mounted on said shank, said

shank and said head having interengaging parts for mounting said head on said shank, means defining openings through each of said interengaging parts, said openings being in alignment when said shank and head are mounted in operative relation, a key insertable in said openings for locking said head on said shank, a bore extending longitudinally of said shank and communicating with the shank opening into which the key is inserted, and a pin slidably mounted in said bore and movable into interengagement with said key, and means for releasably holding said pin in locking position.

10. In a rotary crusher, a hammer shank, a hammer head, a key engaging said head and said shank for detachably mounting said head on said shank, and a smooth locking pin slidable in a longitudinal bore in said shank into interengagement with said key for locking said head on said shank, and also slidable in said bore for releasing said key without removal of the pin.
